UNITED STATES PATENT OFFICE.

BENJAMIN W. LAYTON, OF LYONS, KANSAS.

NUT OR BOLT LOCK.

1,149,454.

Specification of Letters Patent. Patented Aug. 10, 1915.

Application filed August 22, 1914. Serial No. 258,045.

To all whom it may concern:

Be it known that I, BENJAMIN W. LAYTON, a citizen of the United States, residing at Lyons, in the county of Rice and State of Kansas, have invented certain new and useful Improvements in Nut or Bolt Locks, of which the following is a specification, reference being had to the accompanying drawings.

10 My invention relates to a certain new and useful device which I designate as a nut or bolt lock. It has for its object simplicity and economy of construction and is adapted to be placed in operative relation with 15 either a nut or the head of a bolt by the use of a simple hammer.

With these ends in view, my invention consists in the details of construction herein-after more particularly described.

20 In order that those skilled in the art to which my invention appertains may know how to make and apply my improved lock and to appreciate its advantages, I will now proceed to describe the same referring by 25 numerals to the accompanying drawing in which—

Figure 1— is a top plan view. Fig. 2— is a section on the line *a—a*, of Fig. 1— and showing the securing barbs turned up and 30 adapted to penetrate the wood through which a bolt may pass—and Fig. 3 is a sectional view showing a bolt passed through a piece of timber and with one of my improved locks in position over the head of the 35 bolt and another over the nut secured in place upon the threaded end of the bolt.

Similar numerals indicate like parts in the several figures of the drawing.

1 represents preferably, a disk of sheet 40 metal of suitable gage to secure adequate strength, and cut as at 2 on each side of its periphery to form pointed barbs 3 adapted to be bent at approximately right angles to the face of the disk. The barbs 3 are formed 45 by cutting the disk inwardly from its periphery in opposite directions, the cuts terminating at diametrically opposite points. The cut portions of the disk are adapted to be bent at right angles to the 50 plane of the disk, at the terminations of the cuts, as shown by the dotted lines in Fig. 1. When the cut portions are bent to an oppo-

site position, as shown in Fig. 2 of the drawing, they provide inwardly curved barbs which are tapered to points at their extremities so that the barbs may easily be forced into the timber, as shown in Fig. 3.

The disk is punched out at 4 to embrace the sides of the head 5 of a bolt 6 or a nut 7 secured to the threaded end of a bolt.

By reference to Fig. 3 it will be readily understood that when a bolt has been placed in position through a timber 8, a disk 1 may be placed over the head 5 with the barbs 3 driven in the timber, and that in a similar manner a disk may be secured in place over a nut 7. If placed only upon the head of a bolt, it will be obvious that a nut 7 may be run on or off the threaded end of the bolt, and the latter will be securely held against turning in the timber, and similarly if used in connection with a nut only, the bolt may be unscrewed from the nut while the latter is held against movement.

While I have shown the locking device in the form of a disk and the central opening 4 square, it will be understood that the plate may be of any other design and the opening in the center may be polygonal or any other shape, according to the character of the bolt or nut with which it is to be used, and it will also be understood that I do not wish to be confined in any degree to dimensions.

What I claim as new and desire to secure by Letters Patent is—

A nut lock including a circular metallic disk having a centrally located non-circular opening adapted to receive an element to be held, and a plurality of retaining spurs formed integrally with the disk, said spurs being produced by arcuate kerfs cut inwardly from the edge of the disk and by bending the segmental portions freed by the kerfs to lie in a plane at right angles to the plane of the disk, the faces of said segmental portions being disposed in planes comprehending radii of the disk.

In testimony whereof I hereunto affix my signature in the presence of two witnesses.

BENJAMIN W. LAYTON.
